(57) **CLAIM**

The ornamental design for a catheter tip with electrode panel(s), as shown and described.

DESCRIPTION

FIG. 1 is a front view of an electrode panel.

FIG. 2 is a perspective view of the electrode panel of FIG. 1.

FIG. 3 is a perspective view of a catheter tip with the electrode panel of FIG. 1.

FIG. 4 is a front view of the catheter tip of FIG. 3.

FIG. 5 is a rear view of the catheter tip of FIG. 3.

FIG. 6 is another perspective view of the catheter tip of FIG. 3; and,

FIG. 7 is a side view of the catheter tip of FIG. 3.

The broken lines in FIGS. 1-7 depict environment only and form no part of the claimed design.
